(57) **CLAIM**

We claim the ornamental design for a hardhat, as shown and described.

DESCRIPTION

FIG. 1 is a perspective view of the hardhat in accordance with the present invention;

FIG. 2 is a front view thereof;

FIG. 3 is a rear view thereof;

FIG. 4 is a top view thereof;

FIG. 5 is a bottom view thereof;

FIG. 6 is a right view thereof; and,

FIG. 7 is a left view thereof.

The portions of the drawings depicted in dotted lines are included for environmental purposes only, and form no part of the claimed invention.
